GRATE FIRED FLUID HEATING UNIT

Ralph C. Huston, Wadsworth, Ohio, assignor to
 The Babcock & Wilcox Company, Rockleigh,
 N. J., a corporation of New Jersey

Application March 6, 1948, Serial No. 13,369

7 Claims. (Cl. 122—4)

1

The present invention relates in general to the construction and operation of a fluid heater having a grate-fired furnace, particularly with reference to the disposition of fluid heating surface associated with the furnace walls.

In fluid heaters of the vapor generator or steam boiler classification, it is common practice to employ grate-fired furnaces having fluid cooled side walls in which rows of upright fluid conducting tubes are connected to headers arranged marginally of the grate, make-up liquid being fed to the headers at intervals along their lengths. Such headers are necessarily of relatively large cross section and for the higher boiler operating pressures are necessarily of heavy wall thicknesses. When thick walled headers are installed marginally of a grate, it is found that heat cracks often develop in header surfaces directly exposed to the burning bed of fuel, sometimes after only limited periods of service. This is due to the high temperature gradient through the thick header wall which causes the wall metal to become overheated. The effect is accentuated when the furnace is operated under forced draft, as a result of the higher temperatures involved, and particularly when blow holes are formed in thin areas of the bed and localized zones of intense heat are created, the risk of damage to metals adjacent the firing zone ordinarily being increased when coals of a bituminous character are employed.

A purpose of my invention therefore is to provide a grate fired fluid heating unit in which fluid cooled furnace wall areas may be directly exposed to the burning bed of fuel with a minimum risk of injury to the metal of fluid conducting elements, irrespective of the character of fuel being burned.

Another object pertaining more particularly to the construction of a grate fired fluid heater furnace, having fluid conducting elements of relatively large cross section marginally of the grate, is to provide a fluid cooled metallic barrier or shield between such elements and the bed of fuel, the barrier to be formed of tubes of relatively small cross section so as to enable tubes having relatively thin walls to be used for a given operating pressure as compared with the relatively thick walled fluid conducting elements of larger cross section.

A further object is to arrange the tubular heat barrier in such manner as to be more readily renewable than the fluid cooled element shielded thereby.

An object is also to support the tubular barrier unit from the shielded element and to pro-

2

vide for the circulation of fluid therethrough in parallel with the main circulatory system of the fluid heating unit.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described selected embodiments of my invention.

Of the drawings:

15 Fig. 1 is an elevational view in section of a stoker fired vapor generating unit including an illustrative embodiment of my invention;

Fig. 2 is a partial vertical section of the unit shown in Fig. 1, taken along line 2—2;

20 Fig. 3 is a fragmentary detailed enlargement of Fig. 1 featuring the fluid-cooled structure adjacent the grate;

25 Figs. 4, 5 and 6 are transverse sections taken respectively along lines 4—4, 5—5, and 6—6, of Fig. 3; and

Fig. 7 is a fragmentary enlargement of Fig. 3, rotated through 90°.

The vapor generating unit as illustrated in Fig. 1 comprises a steam boiler of the bent tube type having its major convection heating surface 30 provided by banks of tubes 12, 13, 14 extending between and connected to an upper, steam and water drum 15 and a lower, muddrum 16, a superheater 17 having steam inlet connections 18 from drum 15 being disposed between the front tube bank 12 and the intermediate tube bank 13. A stoker fired boiler furnace 19, having its combustion chamber 21 arranged forwardly of the front boiler bank 12, is provided with fluid cooled boundary walls comprising side walls 23, of which one only is shown, a front wall 24, a rear wall 25, and a roof 26. The stoker firing apparatus includes a traveling chain grate 27 having its top run 28 movable from front to rear across the bottom 35 of combustion chamber 21 and receiving coal or other solid fuel delivered thereto from stoker apparatus 29 arranged exteriorly of the furnace adjacent the lower end of its front wall 24. Air for combustion is delivered under pressure in 40 of suitable known manner to the space between the upper and lower runs of the grate. A chain guide member 31, or series of such members, is disposed along each margin of the top run 28 and mounted in known manner on the grate supporting structure. An ash discharge hopper or

pit 32 is provided adjacent the rear end of the grate.

Furnace walls 23, 24 and 25 are cooled by fluid conducting tubes 23a, 24a, and 25a, respectively, while the roof 26 is cooled by upper extended portions of the front wall cooling tubes 24a, and all furnace wall cooling tubes are connected into a natural circulatory system which includes boiler drums 15 and 16 in a manner hereinafter more fully described.

A lower portion of front furnace wall 24 is inclined upwardly and rearwardly to provide an ignition arch 34 above a front portion of the grate 27, while a lower portion of the rear furnace wall 25 is inclined upwardly and forwardly to provide an arch 35 above a rear portion of the grate, the arches 34 and 35 cooperating to define a throat passage 36 of smaller gas flow area than the combustion regions immediately upstream and downstream thereof. A wall 37 extends from the upper end of rear arch 35 to the lower boiler drum 16 to provide an outer boundary wall portion of the boiler tube space.

The front wall tubes 24a are connected at their lower ends to a header 38 which extends horizontally above the grate 27, in upwardly spaced relation thereto adjacent the lower end of the front ignition arch 34, the lower portions of tubes 24a extending upwardly adjacent the inner face of the arch and having their exposed surfaces protected by a layer of heat refractory material 39 applied thereto. The upper ends of tubes 24a are connected to the upper boiler drum 15.

The rear wall tubes 25a are connected at their lower ends to a header 41 disposed rearwardly of the grate 27, beyond the ash pit 32, and extending horizontally at an elevation below the top run of the grate, the header 41 having tubular make-up water connections 42 with the lower boiler drum 16. The upper ends of tubes 25a are connected to the upper boiler drum 15 between the connections provided for the tubes of boiler banks 12 and 13. The lower portions of tubes 25a extend upwardly adjacent the inner face of the rear furnace wall 25 where they are directly exposed to furnace heat whereas, above the wall 25, intermediate portions 25b of these tubes are inclined rearwardly and upwardly to provide support for a baffle 43 which defines, with roof 26, a passageway 45 through which heating gases are directed into contact with convection heated surfaces of the boiler and superheater. An upright baffle 47, disposed adjacent the forward side of tube bank 13 and constituting an upper extension of baffle 43, terminates in downwardly spaced relation to the upper boiler drum 15 to define an entrance for gases into the space containing tube banks 13 and 14, the gases discharging from the space through outlet 48.

In each side wall 23, a circular lower side wall header 50 extends horizontally adjacent the top run 28 of the grate, each header 50 having the lower ends of tubes 23a of the associated wall 23 connected thereto, and having tubular make-up water connections 51 with the lower boiler drum 16, the make-up connections or tubes 51 having their lower ends connected to the respective headers 50 at spaced intervals therealong as indicated in Fig. 3. The upper ends of tubes 23a in each side wall 23 are connected to an upper header 52 from which riser tube connections 53 extend to the upper boiler drum 15.

Each header 50 is supported at intervals along its length by means of support members 54 and 56 mounted on a plate 57 associated with the

grate supporting structure. As shown, each member 54, adjacent the rearward end of each header 50, is in the form of a rectangular plate vertically aligned with the centerline of the header and having its upper edge secured by welds 58 to the header and its lower edge secured by welds 59 to plate 57. Each member 56, as shown, includes a rectangular base plate portion 61 together with integral upright plate like

portions 62 and 63 arranged at right angles to each other, the portion 62 being arranged longitudinally of header 50, in vertical alignment with the centerline thereof and having its straight upper edge secured thereto by welds 64, and the portion 63 extending transversely of the header and having its arcuate upper edge conforming to the circular contour of the header and being secured thereto by welds 65. Each support member 56 is permitted to move relative to plate 57 in unison with the longitudinal movement of header 50, each base plate portion 61 being disposed between spaced guide bars 67 suitably secured as by welds 68 to plate 57. Each header 50 is thus free to expand forwardly from its point of stationary support on member 54 adjacent its rearward end.

Each lower side wall header 50 is shielded from contact with the moving bed of burning fuel on the grate by means of a group of tubes 71 extending longitudinally of the header adjacent the furnace side thereof, the tubes 71 being of relatively small diameter as compared with the diameter of a header 50, for example, in a ratio of an order of about 1:3. In each side wall 23, the header protecting tubes 71 have their intermediate length portions straight and parallel to each other, and also parallel to the header 50 with which each group is associated, these intermediate straight length portions also extending beyond the respective headers 50 at both ends. Tubes 71 have their rearward end portions bent downwardly and connected to the rear wall downtake header 41, and have their forward end portions bent upwardly and connected to the front wall uptake header 38. As thus connected, the tubes 71 receive water fed from transverse header 41 and act as water supply tubes to the transverse front header 38, a natural circulation through tubes 71 being induced by the head differential resulting from steam generation in the front wall cooling tubes 24a which extend from the header 38 to the steam and water drum 15.

The tubes 71 are arranged in groups of threes, for example, in the pattern indicated in Figs. 4, 5 and 6, with the lowermost tube of each group resting on asbestos rope 72, or the like, received in a groove in the upper edge of chain-guide 31. As herein illustrated, each tube 71 is in contact with the tube next adjacent, while the uppermost tube is additionally in contact with header 50. Tubes 71 are retained in position adjacent each header 50 by means of tie bolts 73 having their outer ends bent to engage tie loops 74 which are welded to the respective tubes 71, and having their inner ends threaded and received in slots 75 in the respective angle members 76 which are arranged in longitudinally spaced groups as shown in Fig. 3, with the members of each group secured to the headers 50 in longitudinally and circumferentially spaced relation. The inner end of each bolt 73 is fitted with a nut 78 bearing against a washer 79 which is preferably tack-welded to the respective angle member 76 after the associated tube 71 is tied in place. Although not illustrated, the outer bent end of each tie

bolt 73 may be arranged at right angles to the body portion of the bolt and fitted with a nut to facilitate assembly and also to prevent disengagement from within the loop 74. Thus the tie bolts hold the tubes 71 in predetermined parallel relationship to the furnace face of the side wall header while providing for differential expansion with respect thereto. The space between the assembled tubes 71 and each header 50 and support plate 57 is enclosed at its outer side by a plate member 81 having its upper edge portion overlapping and secured to a bar, or bars, 82 attached to header 50, the space thus enclosed being filled with loose asbestos 63, or the like, to provide a seal against the escape of furnace gases.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. In a furnace having a grate associated with the combustion chamber thereof, a fluid conducting header arranged marginally adjacent the fuel supporting surface of said grate, a group of fluid conducting tubes paralleling said header at the side toward said grate, and means tying said tubes to said header and maintaining successive tubes of said group in contacting relationship.

2. In a furnace having a grate associated with the combustion chamber thereof, a fluid conducting header arranged marginally adjacent the fuel supporting surface of said grate, a group of fluid conducting tubes arranged in vertical superjacent succession alongside of and parallel to said header at the side toward said grate, and means tying said tubes to said header and maintaining successive tubes of said group in said superjacent relationship.

3. The combination as defined in claim 2 wherein the tying means is formed of separate components each having a connection to said header and a connection to one of said tubes.

4. The combination as defined in claim 2 wherein the tying means is formed of separate components individually engaging one of said tubes and comprising a loop member secured to the tube and a tension member having one end in engagement with said loop.

5. The combination as defined in claim 4 comprising a group of members secured to said

header at circumferentially spaced positions for engagement by said tension member components.

5 6. In a furnace having a grate in the combustion chamber thereof, a fluid conducting header associated with a wall of said chamber and extending marginally adjacent the fuel supporting surface of said grate, a group of fluid conducting tubes arranged longitudinally of said header at the side adjacent said grate, said tubes being tied to said header by means holding said tubes in predetermined transverse relationship while permitting longitudinal movement thereof relative to said header, and means for supporting said header at longitudinally spaced points by means 10 maintaining said header fixed at one of said points while permitting longitudinal movement thereof at other points therealong.

7. In a furnace having a combustion chamber defined in part by an upright wall arranged at 20 one side of a grate extending across said chamber, a fluid conducting header associated with said wall and extending longitudinally of said grate at an elevation adjacent the fuel supporting surface thereof, a group of fluid conducting tubes arranged at successive elevations along the inner face of said header, means tying said tubes to said header at spaced points therealong while permitting longitudinal movement of said tubes relative to said header, and means for supporting 25 said header at longitudinally spaced points by means maintaining said header fixed at one of said points while permitting longitudinal movement thereof at other points therealong.

RALPH C. HUSTON.
